SAFETY PRESSURE DETONATOR BOMB

Filed Aug. 18, 1944

Robert E. Mitton.

INVENTOR

UNITED STATES PATENT OFFICE

2,471,163

SAFETY PRESSURE DETONATOR BOMB

Robert E. Mitton, Lemon Grove, Calif.

Application August 18, 1944, Serial No. 550,063

2 Claims. (Cl. 102—81.6)

1

One object of the invention is to provide a positive and simplified means to detonate hand grenades, bombs, torpedoes and other explosive charges by the force of impact instantly when such devices contact an objective against which they may be thrown.

Another object is to provide means to prevent the accidental explosion of such devices during shipment or while being handled prior to or during actual use.

A further object is to provide means to produce such devices contrived in a manner to render them safe to handle for variable lengths of elapsed time after the safety pin has been withdrawn, in which no time element begins to run to the peril of the user under such condition and in which effective means is provided to explode the weapon instantly after it has been thrown, obviating the possibility that it may be thrown back.

The said objects are attained by the device to be hereinafter described and explained by reference to the drawing which shows one adaptation of the device.

In the drawing, Figures 1, 3 and 4 are offset sections of the casing walls on line 2—2.

Figure 2 is a section of said walls on line 1—1. Other parts are shown in the respective views as external in place elevations and sections which will be hereinafter designated and referred to.

Each part is represented in each of the several views and designated by similar numerals: a frangible tube forming a sealing partition 5 constructed of blown glass or other suitable fragile material, is mounted in a small reservoir 6 formed by the top casing 7. The said frangible tube is hermetically sealed into the member 8 as shown and arranged to form a communication passage through the member 8 when the frangible tube partition 5 is broken.

A check valve 9 is provided in casing 7 forming an opening into reservoir 6 through which may be passed compressed air, gas or other expansive fluid pressure or chemicals capable of producing such pressure as required.

A sealing washer or gasket 10 is shown between the member 8 and the top casing 7. The bottom case 11, into which the top case is screwed as shown, forms a container 12 into which the explosive charge is loaded. A fragile diaphragm 13 made of thin rubber or other suitable material is mounted as shown between the top casing 7 and the bottom casing 11.

A slidable detonator pin 14 is secured to the said diaphragm by a screw as shown.

2

A removable safety pin 15 is slidably mounted in a lateral hole intersecting the bore in which the detonator pin 14 is mounted in a slightly offset position as illustrated. The said detonator pin is provided with a main and auxiliary annular groove, the main annular groove is designated 16 and the auxiliary groove 17.

A cotter key 18 is provided to normally hold said safety pin in position.

19 A plug 19 is mounted in the bottom case 11 concentrically with the detonator pin formed in a manner to carry a fuse and firing cap at a position designated by the numeral 20.

15 The slidable detonator pin 14 may be provided with suitable expansion rings, preferably of rubber as shown in order to seal the piston action of the said firing pin against leakage, but more particularly to create a slight amount of friction between the detonator pin and the wall of the bore in which it slides, to prevent the movement of said pin except when actuated by positive fluid pressure.

19 Figures 1 and 2 show the frangible tube 5 in section, while Figures 3 and 4 show it as external views of fragmentary parts.

25 All figures show the firing pin, diaphragm screw, and expanding rubber rings as external elevations of these parts in place.

29 Figures 1 and 4 show the safety pin in place as an external elevation of same.

Figure 2 shows the safety pin in section through main annular groove 16.

Figure 3 shows the safety pin removed and approximate position of parts at the instant of detonation.

35 Figure 4 shows the firing pin being prevented from detonating the cap 20 because the safety pin is in the way and also that the safety pin cannot be withdrawn because the firing pin is in the way.

40 The operation of the device is actuated by fluid pressure stored or created in the reservoir 6 surrounding the frangible tube 5.

45 In use, the safety pin 15 is withdrawn and thereafter the device may be safely held for any length of time until it is thrown against an objective. The impact detonates the charge at the instant of impact against the objective by breaking the frangible tube 5 as shown in Figure 50 3, permitting the pressure in the reservoir 6 to pass through the neck of the broken tube and propelling the detonator pin by fluid pressure into the firing cap after breaking the restraining diaphragm 13 as illustrated.

55 In the event the frangible tube 5 becomes

broken during shipment or at any other time when the safety pin has not been fully removed, the fluid propelled firing pin will be stopped short of the firing cap by the safety pin and by projecting into a part of the annular groove in said safety pin will effectively prevent its subsequent withdrawal.

The auxiliary annular groove 17 in the safety pin is provided as an additional safeguard against the possibility that the frangible tube 5 might be accidentally broken after the safety pin 15 has been partially removed, in which case the firing pin would engage and lock the pin by entering the annular auxiliary groove 17 before the safety pin could be completely removed.

The rubber expanding rings are provided on the firing pin piston 5 primarily to prevent the movement of said firing pin out of its locking position before the bomb has been disassembled or the firing cap 20 removed.

It is noteworthy that the principle of operation disclosed herein would be safer than other types of detonators in many different respects and especially through the elimination of the necessity of the user to accurately estimate the passage of a minute interval of elapsed time, particularly when utilized by a multitude of individuals, each possessed of different judgement and temperamental qualifications, to be used during moments of danger and consequent extreme mental stress.

Having thus described and illustrated my invention, I desire to secure by Letters Patent and claim:

1. In a device of the class described, a chamber containing fluid under pressure, a frangible member sealing an opening from said chamber, a cylinder connected with said opening, a firing pin carried by a piston slidable in said cylinder, a detonator positioned to be struck by said firing pin when said frangible member is broken and said fluid acts upon said piston to move said firing pin into contact with said detonator, a cross bore

intercepting said cylinder between said firing pin and said detonator, a removable safety pin positioned in said bore to prevent said firing pin from striking said detonator, a reduced portion on said safety pin where said pin crosses said cylinder whereby premature breaking of said frangible member will drive said firing pin into said portion and prevent removal of said safety pin.

2. In a device of the class described, a casing, 10 a chamber in said casing containing fluid under pressure, a frangible member sealing an opening from said chamber, a cylinder in said casing connected with said opening, a firing pin carried by a piston slidable in said cylinder, a frangible member attached to said casing and said piston to hold said piston in a fixed position, a detonator positioned to be struck by said firing pin when said frangible member is broken and said fluid acts upon said piston to break said frangible member and to move said firing pin into contact 20 with said detonator, a cross bore intercepting said cylinder between said firing pin and said detonator, a removable safety pin positioned in said bore to prevent said firing pin from striking said detonator, a reduced portion on said safety pin where said pin crosses said cylinder whereby premature breaking of said frangible member will drive said firing pin into said portion and prevent removal of said safety pin.

ROBERT E. MITTON.
